UNITED STATES PATENT OFFICE.

JULIUS LIBROWICZ, OF NEW YORK, N. Y.

DESIGN FOR A BASE OR PEDESTAL.

SPECIFICATION forming part of Design No. 22,165, dated January 31, 1893.

Application filed November 3, 1892. Serial No. 450,905. Term of patent 7 years.

To all whom it may concern:

Be it known that I, JULIUS LIBROWICZ, a citizen of the United States, residing at New York, county of New York, and State of New York, have invented and produced a new and original Design for a Base for a Pedestal or Statue, of which the following is a specification.

The body of the base is of trunco-pyramidal form having a squared or rectangular sub-base 1, from which extends the beading 2 having a raised or depressed continuous line of ornamentation, and at the corners also, which ornamentation is mainly foliated. Above the beading is a horizontally disposed angular fluting 3, and above this lies the body or main portion 4, which, as before described, is in the shape of a truncated pyramid. The face of

the body 4 is ornamented so as to simulate masonry as at 5, and each side of the body is provided with a trapezoidal panel or tablet 6, which lies within the plane of the surface ornamentation, and is defined by a raised border 7 similar in shape. Above the body 4 lies an ornamental cornice beading 8, surmounted by a square or rectangular cap 9.

I claim:

The design for a base for statuary as herein described and shown.

Signed at the city, county, and State of New York this 2d day of November, 1892.

JULIUS LIBROWICZ.
